Primary Examiner — Eric L Goodman*Assistant Examiner* — Vincent T Andrews(74) *Attorney, Agent, or Firm* — Greenberg Traurig, LLP(57) **CLAIM**

The ornamental design for a robotic lawn mower as shown and described.

DESCRIPTION

FIG. 1 is a perspective view of a robotic lawn mower showing my new design;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a top plan view thereof.

The broken lines depict portions of the robotic lawn mower that form no part of the claimed design.

1 Claim, 6 Drawing Sheets(56)
